PC(57) **CLAIM**

The ornamental design for a cockpit input device, as shown and described.

DESCRIPTION

FIG. 1 is a front perspective view of a cockpit input device; FIG. 2 is a front view of the cockpit input device, with some environmental structure removed for clarity of disclosure. FIG. 3 is a back view of the cockpit input device; FIG. 4 is a first side view of the cockpit input device; FIG. 5 is a second side view of the cockpit input device; and, FIG. 6 is a top view of the cockpit input device, where the bottom view is not illustrated and forms no part of the claimed design.

The broken lines illustrate environment and structure which form no part of the claimed design.
